DESIGN FOR A SPRAY GUN

Fritz Wahlin, Chicago, Ill., assignor to Binks
Manufacturing Company, Chicago, Ill., a corporation of Delaware

Application March 18, 1935, Serial No. 55,926

Term of patent 14 years

To all whom it may concern:

Be it known that I, Fritz Wahlin, a citizen of the United States, residing at Chicago, in the county of Cook and State of Illinois, have invented a new, original, and ornamental Design for a Spray Gun, of which the following is a specification, reference being had to the accompanying drawing, forming part thereof.

In the drawing, Figure 1 is a left-hand side

elevational view of a spray gun, showing my new design.

I claim:

The ornamental design for a spray gun, substantially as shown.

FRITZ WAHLIN.
